UNITED STATES PATENT OFFICE.

LEON W. PERRY, OF DENVER, COLORADO.

EQUILIBRATOR.

1,070,625.

Specification of Letters Patent. Patented Aug. 19, 1913.

Application filed March 1, 1911. Serial No. 611,683.

To all whom it may concern:

Be it known that I, LEON W. PERRY, a citizen of the United States of America, residing at Denver, in the county of Denver and State of Colorado, have invented certain new and useful Improvements in Equilibrators, of which the following is a specification.

My invention relates to equilibrators for aeroplanes and its object resides in the provision of an instrument which by automatic readjustment of its stabilizing or elevating planes, will restore the aeroplane upon which it is installed to its proper position, after its equilibrium has been disturbed.

The improved equilibrator may be associated with any one of the operating levers at present in use to control the position of the various wings or planes required to stabilize and steer the aeroplane and its connections are such that, if so desired, the levers may be manually operated without interference with the operation of the parts comprised in the present invention.

The equilibrator comprises, in brief, a metallic spherical weight loosely supported in an arcuate runway which is mounted to oscillate about a horizontal axis coincident with that of the lever which connects with the stabilizing or steering planes. The runway which is partly composed of non-conductive material has at opposite sides of a division, normally located at the point of intersection of a perpendicular passing through the axis of oscillation and the center of the weight, contact blades which constitute the terminals of a normally open electric circuit and which are disposed to be electrically connected by the weight if by reason of a slanting position assumed by the aeroplane when its equilibrium is disturbed, the above mentioned division is moved out of the said perpendicular and from below the weight which it normally supports. Electro-magnetic devices located in the circuit thus closed by the movement of the runway with the aeroplane, are designed to move the runway about its axis until it has reassumed its normal position when the circuit is again

broken and this movement of the runway is by means of the operating lever with which it is associated, converted into a corresponding movement of the stabilizing planes which by increasing or diminishing the wind resistance at opposite sides of the main

planes of the aeroplane, restore its equilibrium. The operating lever above referred to is adjustable relative to the runway, to change the position of the stabilizing or steering planes with relation thereto, and an electric brake is provided to maintain the parts in their normal position while the aeroplane is in equilibrium. If it is desired to automatically control the stabilizing wings at opposite sides of the main plane, as well as the plane or planes by means of which the aeroplane is directed up or downwardly, a separate equilibrator is required for each set of planes and it will be understood that while in the drawings the device has been shown in association with stabilizing planes or so called "ailerons", it may be used with equal effect in connection with the warping wing tips or other devices which in certain air ships are provided to maintain the lateral stability thereof. Attention is further called to the fact that my invention is not only adapted to restore the aeroplane to its proper position after its equilibrium is accidentally disturbed but that it also serves to give to the ship the proper "bank" while rounding curves and that it furthermore permits of unequal distribution of weight upon the ship, by a compensating adjustment of the stabilizing planes.

In the drawings, in the various views of which like parts are similarly designated, Figure 1, represents a front-view of an aeroplane with my invention installed in connection with ailerons applied at opposite sides of the center thereof, Fig. 2, a side view of an aeroplane showing the invention in association with the forward elevating or tilting plane, Fig. 3, a sectional elevation of the instrument drawn to an enlarged scale, Fig. 4, a section taken along the line 4-4 Fig. 3, Fig. 5, a diagrammatic view of the electric circuit by which the oscillatory runway is actuated, Fig. 6, a horizontal section taken along the line 6-6, Fig. 3, Fig. 7, a similar section along the line 7-7 Fig. 3, and, Fig. 8, a vertical section through the runway.

Referring to the drawings by numerals, 2 designates a base-plate which, in practice, is secured upon the aeroplane in a normally horizontal position. Standards 3 erected upon the base 2 support a horizontal shaft 4 upon which the operating lever 5 and the

runway 6 are independently movably mounted. The segmental runway 6, whose arc is concentric with the shaft 4, is suspended therefrom by means of a sector-shaped web 7 which at its opposite side is provided with a concentric series of teeth 8 which serve to lock the operating lever in its adjusted position with relation to the runway. The lever 5 is, to this end, made partly tubular and provided at its lower extremity, with a longitudinally slidable dog 9 which at its lower surface, has a plurality of teeth adapted to enter the interdental spaces of the series 8, in which position they are maintained by means of a coiled spring 10. A bent lever 12 is fulcrumed at the upper end of the lever 5 and is connected by means of a rod 13 with the dog 9 to disengage it from the teeth on the runway when it is desired to vary the position of the operating lever with relation thereto.

In Figs. 1 and 2 of the drawings the numeral 14 designates the aeroplane on which the instrument is installed, 15 the stabilizing planes articulately mounted at opposite sides thereof, and 16 the elevating plane which controls the up and downward movements of the ship. The various stabilizing planes may be connected by means of an endless rope 17 (as in Fig. 1) or a rod 18 (as in Fig. 2), either directly with the operating lever 5 or with an arm 19 secured upon the end of the shaft 4. The last mentioned construction has the advantage that, by means of a set-screw 20, the arm 19 may be adjusted to any desired position on the shaft for the purpose of changing or reversing the relative movements of the planes with which it is connected.

The segmental runway 6 which extends along the arcual edge of the sector 7 at one side thereof, is made of fiber or other non-conductive material in the upper surface of which are laid four contact plates, best shown in Figs. 5 and 6, one of which, 21, is continuous from one end of the runway to the other, while the other three, respectively designated by the numerals 22, 23 and 24, are arranged consecutively in parallel relation thereto. The central one, 23, of the three consecutive plates is, normally disposed in the perpendicular which passes through the axis of the shaft 4 and the center of the spherical, metallic weight 25, which is loosely supported in the runway and which by its gravitational tendency is the prime factor in the operation of the invention. The oscillatory runway is furthermore provided with a segmental worm-gear 26 which extending along its lower surface, is in mesh with a worm 27 which is mounted to move about a horizontal axis in bearings 28 upon the base 2. The shaft 29 of the worm carries at one of its ends, a beveled

friction wheel 30 which is disposed to be engaged by either one of two friction cones 31 which are slidably mounted upon a shaft 33 mounted transversely to the shaft 29 in bearings 34 on the base.

In the operation of the invention, the shaft 33 is continuously in motion and is, to this end, connected with the aeroplane motor by means of a flexible shaft 35 shown in Fig. 7, or it may be connected with a separate propeller which is rotated by the air-current while the ship is in motion.

The two cones 31 are connected with the ends of two shift-levers 32 which are fulcrumed upon pedestals 36 on the base and whose opposite extremities carry the armatures of two axially aligned electro-magnetic coils 37. A coiled spring 38 which connects the last mentioned extremities of the levers 32, is provided to return them to their normal positions, in which the cones are disengaged from the friction-wheel 30, after the magnets are deenergized.

A friction-disk 39 mounted upon the end of the worm shaft opposite to that which carries the beveled wheel 30, is provided to rigidly maintain the parts in their normal position, by engagement with shoes 40, respectively secured at the ends of two brake-levers 41 which are fulcrumed upon pedestals 42 on the base and which carry at their opposite ends, the armatures of two axially aligned electro-magnetic coils 43. A coiled spring 44 connecting the ends of the levers 41, serves to separate the shoes 40 from the peripheral edge of the disk 39, when the magnets 43 are deenergized.

The runway proper upon which the weight 25 is supported, is inclosed by a casing 45 which not only excludes dust and dirt but which also prevents sparks resulting from the breaking and making of the electric circuit when the separated contacts are consecutively brought in engagement with the weight, from igniting inflammable matter such as the gaseous fluid by which the aeroplane motor is operated.

Referring to the diagrammatic representation in Fig. 5 of the drawings, the continuous contact-strip 21 is connected with a suitable source of electricity 46, whose opposite pole is in electric connection with the various magnetic coils 37 and 43. The electro-magnets 43 which control the movements of the brake-levers 41 are connected in series with the central contact plate 23 while the magnets 37 which control the movements of the friction-cones 31, are respectively connected with the contact strips 22 at opposite sides of the plate 23. When the parts are in their normal position, as is shown in the drawings, the spherical weight 25 is supported upon the central plate 23 and the continuous contact-strip 21 thus closing the circuit of the electro-magnets 43 which

by attraction of their armatures maintain the shoes 40 in frictional engagement with the peripheral edge of the disk 39.

The normal position of the stabilizing or 5 tilting planes of the aeroplane, is established by the position of the lever 5 relative to the runway; for example, when the aeroplane under ordinary conditions, moves in a horizontal direction, the planes will all extend 10 horizontally and the lever is perpendicular as shown in Fig. 3; should the ship carry an excess of weight at one side of its center of gravity, the stabilizing planes, are, by adjustment of the lever, slanted to compensate 15 for the unequal distribution of the weight, and thus maintain the ship on an even keel, or in case the instrument is connected with the elevating plane, the latter is slanted by means of the lever 5 in accordance with the 20 desired angle of inclination during the up or downward movement of the aeroplane. In any case, irrespective of the position of the lever 5, the runway will normally occupy a position in which the central contact plate 23 25 intersects the perpendicular passing through the axis of oscillation and the center of the weight, and when by deflection of the aeroplane it is temporarily displaced, it will, by the action of the magnets as will 30 hereinafter be explained, be at once returned to its normal position and thus cause a re-adjustment of the planes connected with the lever 5. When by disturbance of its equilibrium, the aeroplane tilts in a plane sub- 35 stantially parallel to that in which the runway of the equilibrator, is movable, the contact plate 23 of the latter is moved out of the perpendicular passing through its axis of oscillation and the center of the weight 40 25 and the latter, which by its gravitational tendency remains in its normal position, is in consequence brought in contact with the strip at the lower side of the plate 23 while it remains in engagement with the continu- 45 ous strip 21. The result is that the magnets 43 are deenergized which releases the friction disk 39, and that the magnet 37 corresponding with the contact strip engaged by the weight will be energized by the closing 50 of its circuit and thus by attraction of its armature at the end of the corresponding lever 32, bring the respective cone 31 on the continuously rotating shaft 33 in frictional engagement with the wheel 30 which through 55 the instrumentality of the worm, moves the runway about its axis of rotation until it has been restored to its original position relative to the perpendicular passing through the said axis when the ball 25 by engage- 60 ment with the contact plate 23, arrests further movement by energization of the brake-magnets, while the magnet 37 whose circuit had previously been closed, is simultaneously deenergized. Should the operator of the 65 aeroplane desire to change its course by ad-

justment of the rudder, the movement of the ship about a radial point, will cause the ball 25, impelled by centrifugal force, to move in the runway to a point where the forces of gravity and centrifugal action coincide, 70 and the runway which by the contact of the ball with the respective strip 22 and the consequent energization of the corresponding magnet 37, is, so to speak, compelled to "follow" the ball, will move the planes connected with the lever 5, to maintain the aeroplane at the proper angle of inclination during its circular movement. It will thus be observed that irrespective of the cause, any disturbance of the equilibrium of the aeroplane, will be instantly corrected by the action of the oscillatory runway which when moved from its normal position with respect to the perpendicular passing through its axis, will immediately be impelled in the direction opposite to that in which it was displaced until it has re-assumed its normal position, and this return movement is converted into a movement of the adjusting planes connected with the runway, to restore the aeroplane to the position in which it is in equilibrium. 85 90

Having thus described my invention, what I claim is:—

1. An instrument of the class described comprising an oscillatory runway having electric contacts at opposite sides of a contact normally in the perpendicular passing through the axis of oscillation, a conductive weight loosely supported on the said runway, electric means in a circuit with the said mediate contact for locking the runway in its normal position, and suitable mechanism in an electric circuit with the contacts at opposite sides of the said mediate contact, and adapted to restore the runway to its normal position relative to the said perpendicular after said contacts at one side or the other, have been electrically connected by the weight during displacement of the runway 11 in the plane of its oscillatory movement. 95 100 105

2. An instrument of the class described comprising an oscillatory runway having a continuous contact strip and three consecutive contacts in a line substantially parallel thereto, the mediate one of the said contacts being normally in the perpendicular passing through the axis of oscillation, a conductive weight loosely supported in said runway and adapted to simultaneously engage the 115 said continuous contact and one of the others, an electro-magnetic device in a circuit with the said mediate contact for locking said runway in its normal position, and electro-magnetic devices, in a circuit with the contacts at opposite sides of the said mediate contact, and adapted to restore the said runway to its normal position relative to the said perpendicular after the contacts at one side or the other have been electrically 120 125 130

connected by the weight during displacement of the runway in the plane of its oscillatory movement.

3. An instrument of the class described comprising an oscillatory runway having a continuous contact strip and two contacts in a line substantially parallel thereto and separated by a space normally in the perpendicular passing through the axis of oscillation, a conductive weight loosely supported on said runway and adapted to simultaneously engage said continuous contact and one of the others, and electro-magnetic devices in a circuit with said continuous contact and said separated contacts and adapted to restore said runway to its normal position relative to the said perpendicular, after one or the other of the said contacts is engaged by the weight during displacement of the runway in the plane of its oscillatory movement.

4. An instrument of the class described comprising an oscillatory runway having contacts at opposite sides of a contact normally in the perpendicular passing through the axis of oscillation, a conductive weight loosely supported on said runway, a rotating shaft, driving transmission members slideable thereon, a driven member operatively associated with said runway, means for locking said driven member against rotation, an electro-magnet the armature of which is connected with said locking means, and electro-magnets whose armatures are connected with the respective driving members to move them in engagement with the said driven member, the first mentioned electro-magnet being in an electric circuit with the mediate contact on the runway, and the two other magnets respectively in a circuit with the contacts at opposite sides of the same.

5. An instrument of the class described comprising an oscillatory runway having contacts separated by a space normally in the perpendicular passing through the axis of oscillation, and a segmental worm-gear, a conductive weight loosely supported on said runway, a rotating shaft, driving transmission members slideable thereon, a rotary worm in engagement with said gear, a driven member connected with said worm, and electro-magnets whose armatures are connected with the respective driving members to move them into engagement with the said driven member, said magnets being respectively in an electric circuit with said contacts.

6. An instrument of the class described comprising an oscillatory runway having a segmental worm-gear and contacts at opposite sides of a contact normally in the perpendicular passing through the axis of oscillation, a conductive weight loosely supported on said runway, a rotating shaft, driving transmission members slideable thereon, a rotary worm connected with said gear, a driven member and a friction-disk connected with said worm, a shoe adapted to engage said disk, an electro-magnet the armature of which is operatively connected with the said shoe, and electro-magnets whose armatures are connected with the respective driving members to move them in engagement with the said driven member, the first mentioned electro-magnet being in an electric circuit with the mediate contact on the runway, and the two other magnets respectively in a circuit with the contacts at opposite sides of the same.

7. In combination with an aeroplane and a steering or stabilizing device thereon, a runway movable about a fixed point on said aeroplane and having electric contacts at opposite sides of a dividing space, normally in the perpendicular passing through the said point, a lever independently movable about the same point, adjustably connected with the runway and connected with the said device, a conductive weight loosely supported on said runway, and suitable mechanism in an electric circuit with said contacts, and adapted to restore the runway to its normal position relative to the said perpendicular, after the contacts at one side or the other of the dividing space have been electrically connected by the weight during displacement of the runway in the plane of its oscillatory movement.

8. In combination with an aeroplane and a steering or stabilizing device thereon, a runway movable about a fixed point on said aeroplane and having electric contacts at opposite sides of a dividing space, normally in the perpendicular passing through the said point, and a concentric series of teeth, a lever movable about the same point, in connection with the said device, a dog movable on said lever, and normally engaging said teeth, a conductive weight loosely supported on said runway, and suitable mechanism in an electric circuit with said contacts, and adapted to restore the runway to its normal position relative to the said perpendicular, after the contacts at one side or the other of the dividing space have been electrically connected by the weight during displacement of the runway in the plane of its oscillatory movement.

In testimony whereof I have affixed my signature in presence of two witnesses.
